CONTAINER

Shy Rosen, New York, N. Y., assignor, by mesne assignments, to Vincent Wright, Alameda, Calif.

Continuation of application Serial No. 465,492, July 3, 1930. This application January 3, 1933, Serial No. 649,837

2 Claims. (Cl. 206—46)

The present invention relates to containers, such as transparent cellulose sheeting, and constitutes a continuation of my co-pending application, Serial No. 465,492, filed July 3, 1930.

Transparent cellulose sheeting, such as the product known as regenerated cellulose, is coming into extensive use for wrapping and packaging purposes. Its use, however, has been more or less haphazard, wrapping therewith having been accomplished more or less in the same fashion as goods are wrapped in ordinary paper.

An important object of my invention is to form finished containers, composed principally of "Cellophane" or the like, which can be sold to the merchant and into which he can readily and accurately fill the commodity to be merchandised.

Another important object is to provide a substantial, economical and practical container which retains a definite shape after having been filled.

A further object is to provide a container which is folded into very small space but which can be readily expanded to receive contents.

A further object is to provide a container of this kind having ample surface for receiving descriptive or advertising matter applied by printing, labels, or otherwise.

A still further object is to provide a container of the type described in which access may be had to the interior thereof without disturbing the wrapping of the container.

Referring to the drawings:

Fig. 1 is a perspective view showing the manner of filling one of my improved containers;

Fig. 2 is a perspective view of a filled and sealed container;

Fig. 3 is a plan view of a container as it is sent to the merchant for filling;

Fig. 4 is a section on plane IV—IV of Fig. 3;

Fig. 5 is a perspective view showing a modified form of container;

Fig. 6 is a plan view of the container as sent to the merchant and before filling;

Fig. 7 is a section on plane VII—VII of Fig. 6;

Fig. 8 is a perspective view showing a modified form of container;

Fig. 9 is a perspective view showing the procedure for filling the container;

Fig. 10 is a plan view of the unfilled container;

Fig. 11 is a section on plane XI—XI of Fig. 10;

Fig. 12 is a plan view of another modified form of container;

Fig. 13 is a bottom view of the container of

Fig. 12;

Fig. 14 is a section on plane XIV—XIV of Fig. 13;

Fig. 15 is a section on plane XV—XV of Fig. 13, showing the manner of expanding and filling the container; and

Fig. 16 is a transverse cross section of the container when expanded and filled.

The containers shown comprise the two elements 1 and 2. The element 1 defines the shape of the container and is of comparatively stiff material such as cardboard. The element 2 is the wrapping or merchandise enclosing element and is preferably a piece of transparent cellulose sheeting, although other suitable material such as paper, parchment, fenestra, glassine, foil, or any combination of these, may be used.

For the container shown in Figs. 1 to 4 a rectangular piece of transparent cellulose sheeting or other suitable material is used, its longitudinal edge sections 3 being folded around and secured to the outer face of the shape defining and backing board 1. The end of the transparent cellulose sheeting is then folded to form the bottom 4 for the container, the corners being first given triangle folds as indicated at 5, and the end section 2 or flap 6 is then secured against the board 1 at the ends thereof. The other end 7 of the transparent cellulose sheeting remains open to receive the merchandise. The purpose of the triangular folds at the bottom is to permit this end of the container to fold in such a position that it will eliminate the surplus transparent cellulose sheeting from extending out from the container in a disorderly fashion.

In the process of assembling the container the transparent cellulose sheeting may be made with tuck-in, satchel, or fold-in sides as best illustrated in Fig. 4. The extent of the fold-in sides determines the depth or capacity of the container. In fabricating a container, a piece of transparent cellulose sheeting is first laid flat on a support, then a suitable template is placed on the transparent cellulose sheeting, and on top of the template is placed the backing board 1. The template may be larger than the board and the difference in dimensions will determine the volume of the container or the extent of transparent cellulose sheeting to be tucked or folded in. The sides of the regenerated cellulose are folded around the sides of the template and secured by suitable adhesive to the board 1 as indicated at 3. The end of the regenerated cellulose for forming the bottom has its corners first folded as has already been described and then this end section is folded around the ends of the template and 55

its flap section 6 is secured to the board. The template is then withdrawn. The container, after formation, is flat and of small volume and can be economically packed and shipped.

5 Referring to Fig. 1 the container can be easily and accurately filled by means of a device such as a scoop 8. The merchandise A, which may be cookies or crackers as shown, is first placed in the scoop and the scoop is then inserted into the 10 open end 7 of the container to bring the merchandise into the body of the container. By then inserting the fingers in front of the merchandise at the outer end of the scoop, the scoop can be withdrawn and the merchandise will be accurately fitted into the container. The end 7 is then folded over, the corners being first folded in, and the end section or flap 7' is secured to the adjacent end of the board 1, as shown in Fig. 2. The container is now fully closed and sealed and 15 the board 1 defines the shape of the container and forms a backing therefor and also a surface for the application of advertising or other information, either by printing thereon or by means of labels. If the wrapping element is of transparent material such as regenerated cellulose, the container contents will be readily visible.

In Figs. 5, 6, and 7 a container is shown for containing candy, nuts, raisins or other small sized commodities. Like the container in Figs. 30 1 to 4, this container comprises a backing board 9 and a wrapping material 10 of regenerated cellulose or other suitable material. The wrapping element is secured along its edges to the longitudinal section of the board 9 and the ends of the 35 wrappers are both secured to the board when the container is made. In order that the container may be filled the board has an opening 11 which may be formed by severing a section 12 therefrom along three sides so that this section may serve 40 as a closure hinged along the line 13. The wrapper element may be folded or tucked in along its sides as shown in Fig. 7 so that the container will occupy the least space for compact and economical shipping purposes. When the container 45 is to be filled the lid 12 is swung open and the contents poured in through the opening 11. The lid is then swung to closed position and may be so held by gummed strips 14 shown, or by means of labels or otherwise. These strips or labels 50 can be readily cut or broken when it is desired to open the lid to extract the contents of the container.

In Figs. 8 to 10 a container is shown adapted 55 particularly for receiving commodities such as bacon. The container is constructed in the same manner as the container of Figs. 1 to 4 except that it is not so deep, and the sides of the regenerated cellulose wrapper 14 are folded outwardly as indicated at 15 in Fig. 11. A scoop or tray 16 60 with the bacon contents thereon is inserted between the wrapping element 14 and the backing board 17, as illustrated in Fig. 9, the scoop being then withdrawn and the sealing end of the wrapper is then folded around the adjacent end of the backing board 17 and secured thereto as shown in Fig. 8.

On Figs. 12 to 16 another modified arrangement is shown. In some cases the contents of the container must be better protected against

crushing as for example in the packaging of candies such as jelly bars or bars filled with liquid or semi-liquid condiment. For such packaging I preferably provide side wall sections 19 and 20 and end walls 21 and 22 for the backing board 23. 5 When the container is made the wall sections 19, 20, and 21 are folded against the backing board 23 while the end wall 22 at the sealing end extends outwardly, as shown in Figs. 13 and 15. The transparent cellulose sheeting or other wrapping element 24 is secured along its longitudinal sides against the bottom of the board 23 and bridges over the top of the board and the folded down side walls thereof. One end of the wrapper is folded and secured to the adjacent end of the 10 backing board, while the sealing end 26 remains open. To fill the container the contents therefor are placed in a scoop 27 having its side walls beveled at the front as indicated at 28. The bottom of the scoop and its inclined edges 28 are 15 inserted between the wall end 22 and the folded down side wall sections 19 and 20 and then as the scoop is moved inwardly these side wall sections will be raised. The end of the scoop will engage under the folded down end wall 21 and will also 20 raise this wall section and after withdrawal of the scoop the contents retained in the container will hold the side wall sections in perpendicular position. The end wall section 22 is then folded up and the wrapper end 26 is folded therearound 25 and secured against the bottom of the backing board. The backing board with its vertical walls will form a rigid container which will protect the contents against pressure and crushing, and the wrapper of transparent cellulose sheeting or other 30 material will cover over and protect the contents and make them visible to prospective purchasers.

The various forms of containers shown are flat so that they can be readily packed into small compass in ordinary rectangular cartons or containers. The folding of the wrapper elements at the sides and ends is accurately gauged so that when the container is expanded it will give the 35 right capacity for the volume of merchandise to be received therein.

It is evident that changes may be made in the size, shape, construction and arrangement of the container without departing from the scope and principles of the invention and I do not, therefore, desire to be limited except as specified in the 40 appended claims.

I claim:

1. In a container; a bottom wall; top, side and end walls folded from a single sheet of tough flexible transparent material and permanently 45 secured to the bottom wall; and a door in said bottom wall giving access to the interior of the container so that the contents thereof may be reached without disturbing the upper portions of the container.

2. In a container; a bottom wall of relatively 50 stiff material; top, side and end walls formed from a single sheet of flexible transparent material adhesively united to the bottom wall; and a door in said bottom wall giving access to the interior of the container so that the contents thereof may be reached without disturbing the upper 55 portions of the container.

SHY ROSEN.
